(57) **CLAIM**

We claim the ornamental design for a dental cleaning appliance, as shown and described.

DESCRIPTION

FIG. 1 is a perspective view of a dental cleaning appliance showing our new design;

FIG. 2 is a front elevation view thereof;

FIG. 3 is a rear elevation view thereof;

FIG. 4 is a side elevation view thereof;

FIG. 5 is a side elevation view of the opposite side of FIG. 4;

FIG. 6 is a top plan view thereof; and,

FIG. 7 is a bottom plan view thereof.

Portions of the dental cleaning appliance shown in FIGS. 1-6 are illustrated with gray shading to show contrast. The shaded cylindrical portion is a different color than the remainder of the dental cleaning appliance.

The broken lines shown in the drawings illustrate portions of a dental cleaning appliance that form no part of the claimed design.
